UNITED STATES PATENT OFFICE.

JOHN B. VAN HOUTEN, OF NEWARK, NEW JERSEY.

DESIGN FOR AN EAR-RING AND PENDANT.

SPECIFICATION forming part of Design No. 14,517, dated December 25, 1883.

Application filed July 29, 1883. Term of patent 7 years.

To all whom it may concern:

Be it known that I, JOHN B. VAN HOUTEN, a citizen of the United States, residing at Newark, in the county of Essex and State of New Jersey, have invented and produced a new and original Design for Ear-Rings and Pendants; and I do hereby declare the following to be a full, clear, and exact description of the same, such as will enable others skilled in the art to 10 which it appertains to make and use the same, reference being had to the accompanying drawings, and to letters of reference marked thereon, which form a part of this specification.

Referring to said drawings, Figure 1 is a front 15 elevation of an ear-ring or pendant, and Fig. 2 is an end view of the same.

The leading feature of this design is more especially in connection with the pendant portion of the ornament, which feature will be 20 hereinafter described, and embodied in the claim.

In said drawings, the parts A B C, which engage with the ear, may be of any appropriate design, inasmuch as the novel features in

the conformation of the ear-ring are in the pendant. The central portion, G, of the pendant is shaped like an annular band, or ring-shaped, across the peripheral face of which, at the top of the pendant, a projecting ridge, E, extends, and at the bottom a flat protuberance, K. At each side of the annular portion the pendant has small projections L, which protrude from the axial center of the ring-shaped portion, and at the outer extremities of the portions L the pendant is button-shaped, as at H I. The peripheral face of the annular band is ornamented with engraved designs and a stone or jewel, J.

What I claim is—

In a design for an ear-ring, the design for a pendant, herein shown and described.

In testimony that I claim the foregoing I have hereunto set my hand this 19th day of June, 1883.

JOHN B. VAN HOUTEN.
